ARMAND H. PEYCKE, OF CHICAGO, ILLINOIS, ASSIGNOR TO AMERICAN STEEL
FOUNDRIES, OF CHICAGO, ILLINOIS, A CORPORATION OF NEW JERSEY.

SUPPORTING AND LEVELING DEVICE FOR CLASP-BRAKES.

1,322,048.

Specification of Letters Patent. Patented Nov. 18, 1919.

Application filed April 5, 1918. Serial No. 226,908.

To all whom it may concern:

Be it known that I, ARMAND H. PEYCKE, a citizen of the United States, and resident of Chicago, in the county of Cook and State 5 of Illinois, have invented certain new and useful Improvements in Supporting and Leveling Devices for Clasp-Brakes, of which the following is a specification.

This invention relates to a supporting and 10 leveling device for clasp brakes.

One of the objects of the invention is to simplify and improve supporting and leveling devices for clasp brakes.

Another object is to provide a pull rod 15 supporting and leveling device adapted to meet the requirements for successful commercial operation.

Generally speaking, these and other objects are accomplished by providing, in 20 brake mechanism, the combination of a pull rod and a hanger therefor forged around the pull rod.

The invention is illustrated on the accompanying sheet of drawings, in which—

25 Figure 1 is a fragmentary plan view of a railway car truck embodying my invention;

Fig. 2 is a fragmentary side elevation of the same; and,

Fig. 3 is a sectional view taken in the 30 plane of line 3—3 of Fig. 2 showing a bracket for supporting the hanger.

The various novel features of the invention will be apparent from the following description and drawings and will be particularly pointed out in the appended claims.

Referring to the drawings, it will be noted that I have shown a railway car truck 10 carried by the car wheels 11, only one of which is shown. Mounted upon opposite

40 sides of each pair of wheels is a brake beam 12 carrying brake heads 13 with brake shoes 14 for frictionally engaging the wheels. The brake beams are provided with fulcrums 15, to each of which is pivotally connected a

45 hanger 16 which assists the regular hangers 17 in supporting the brake rigging. The lower ends of brake levers 18 and 19 are pivotally connected to the fulcrums 15, and connecting these brake levers intermediate 50 their ends is a pull rod 20. The pull rods must be supported and kept properly leveled in order that the braking mechanism may operate properly.

I have provided an improved and simplified supporting and leveling device which in-

cludes a hanger 21, the lower end of which is forged around the pull rod 20 in the form of an elongated loop 22. The pull rod is provided with a plurality of projections 23 between which is formed a seat 24 for the 60 lower end of the loop 22 of the hanger 21. The seat 24 in each case, is formed just outside of the jaws of the pull rod which embraces an intermediate portion of a brake lever. The upper end of each of the pull 65 rod hangers is provided with an eye 25, through which a pin 27 may be passed for supporting the hanger 21, said pin also passing through openings in the loop of a bracket 28, which may be secured to the 70 wheel guard at 29 or to any other suitable support. The hangers 21, therefore, are pivotally mounted in line with each other in a manner to permit the pull rod 20 to swing in accordance with braking conditions and at 75 all times maintain the pull rod in a plane parallel with the tracks. By referring to Fig. 3 of the drawings, it will be noted that sufficient clearance is left in the elongated loop to permit the hanger to swing a considerable amount. The arrangement is such however, that it is not possible for the loop 22 of the hanger to move out of its seat 24 in the pull rod.

By means of this hanger arrangement the 80 pull rod, such as the intermediate pull rod herein shown, may be supported and maintained parallel with the track in a simple and improved manner by forging the lower end of the hangers around the pull rod, 85 thereby obviating the necessity of a pin connection between the pull rods and their hangers.

It is evident that there may be modifications of the invention herein shown and described, and it is my intention to cover all such modifications falling within the spirit and scope of the following claims.

I claim:

1. In brake mechanism, the combination 100 of a pull rod with a seat formed therein and a hanger for said pull rod occupying the seat in said pull rod.

2. In brake mechanism, the combination 105 of brakes, levers operatively connected thereto, a pull rod connecting said brake levers and having a seat formed therein, and a supporting hanger for said pull rod occupying the seat in said pull rod.

3. In brake mechanism, the combination 110

of brakes, levers operatively connected thereto, a pull rod connecting said brake levers and having seats formed therein, and a plurality of hangers occupying said seats for supporting the pull rod and maintaining the same parallel with the tracks.

4. In brake mechanism, a pull rod having a seat therein, and a hanger therefor having an elongated loop, a portion of which occupies said seat, there being sufficient clearance between the elongated loop and the pull

rod to permit a free relative movement therebetween but not enough to permit the loop of the hanger from disengaging said seat.

Signed at Chicago, Illinois, this 28th day of March, 1918.

ARMAND H. PEYCKE.
